UNITED STATES PATENT OFFICE.

BESSIE EVANS CARRAWAY, OF REIDSVILLE, NORTH CAROLINA.

DESIGN FOR A WASHSTAND.

SPECIFICATION forming part of Design No. 34,671, dated June 18, 1901.

Application filed March 1, 1901. Serial No. 49,520. Term of patent 7 years.

To all whom it may concern:

Be it known that I, BESSIE EVANS CARRAWAY, a citizen of the United States, residing at Reidsville, in the county of Rockingham and State of North Carolina, have invented and produced a new and original Design for Washstands, of which the following is a specification, reference being had to the accompanying drawing, forming part hereof, and wherein is illustrated in elevation a view of my new design.

As shown in the drawing, the leading or material features of my design consist of four diametrically-disposed supports 1, presenting a plain flat and comparatively broad surface and bent inward or contracted in their relative positions at their middle and placed or directed outward in bowed curves above and below the middle, as shown, and having their lower or end portions abruptly and sharply curved outward and extended horizontally. At the contracted waist or middle portion of the supports a disk 2 is produced, showing a

plain vertical band 3, and at the top of and extending well down between the standards 1 25 is produced a depending hemispherical body 6, about the upper edge of which is produced a broad plain flaring rim or flange 7, upwardly inclined and outwardly extended, and at the line of union between the flange 7 and 30 the hemispherical depending body 6 is produced an annular bead 5. Intermediate the waist ring or band 3 and the bead 5 is produced a ring 4, resting at its radii against the inner face of the supports 1, all as shown. 35

Having described my invention, what I claim is—

The design for a washstand, as herein shown and described.

In testimony whereof I affix my signature 40 in presence of two witnesses.

BESSIE EVANS CARRAWAY.

Witnesses:

PERCY L. WITHERS,
M. V. EVANS.
